PUSH-BUTTON TUNING CONTROL

Anthony P. Olesky, Chicago, Ill., assignor, by
mesne assignments, to Belmont Radio Corpora-
tion, Chicago, Ill., a corporation of Illinois

Application September 20, 1944, Serial No. 554,935

21 Claims. (Cl. 74—10)

1

The present invention relates to control apparatus and more particularly to improved control apparatus for selectively tuning a radio receiver to desired signal channels. Specifically, the present invention relates to improvements in control apparatus of the character disclosed in co-pending application Serial No. 532,443, filed April 24, 1944, Alexander W. Plensler, and assigned to the same assignee as the present invention. This application issued as Patent No. 2,413,515 on December 31, 1946.

Various push button actuated mechanically controlled devices are commercially available for selectively actuating the tuning elements of a radio receiver to settings corresponding to particular desired transmitting stations. The usual device of this character employs a rotatable tuning or control shaft having a plurality of heart-shaped station selector cams or control elements spaced axially therealong, which are adapted to be engaged by cam rollers rotatably carried by movable push button actuated manuals arranged transversely of the tuning shaft; the arrangement being such that when any manual is actuated, the associated cam roller and control element are engaged to move the tuning shaft to a setting corresponding to a predetermined signal channel. In at least one commercial version of this device, facilities including a manually operable actuating element in the form of a second shaft extending normal to the tuning shaft through the front wall of the receiver, are provided at one end of the tuning shaft for the purpose of manually rotating the tuning shaft to station receiving settings other than those to which the tuning shaft may be operated by the manuals, and for the additional purpose of releasably exerting a restraining force upon the control elements in a direction axially of the tuning shaft to permit adjustment of each control element relative to the tuning shaft.

In general, it is an object of the present invention to provide in control apparatus of the character described, an improved, simple, cheap, rugged and reliable device including a common manually operable actuating element, for releasably locking the control elements against rotation relative to the control shaft upon which they are mounted and for selectively actuating the shaft to any desired setting within a predetermined range of rotation.

According to another object of the invention, the improved control element locking and shaft actuating device is so arranged that each axial movement of the manually operable actuating

5

2

element is used either to clamp or unclamp the control elements, thereby to prevent or permit adjustment of the elements relative to the control shaft, without interrupting the driving connection between the actuated element and the control shaft.

It is another object of the invention to provide an improved and exceedingly simple arrangement for maintaining a driving connection between the manually operable actuating element and the control shaft at all axial settings of the actuating element within its range of axial movement, without in any way interfering with movement of the actuating element between its two extreme axial settings.

In accordance with a further object of the invention, a compression spring carried by the control shaft is provided in the device for normally restraining the control elements against movement relative to the control shaft, and an improved lever and cam mechanism controlled by axial movement of the actuating element is provided for actuating this spring to either restrain the control elements against movement relative to the control shaft or release these elements for rotation relative to this shaft.

According to a further and more specific object of the invention, the lever camming facilities are provided with an exceedingly simple over-center arrangement for positively restraining the manually operable actuating element in either of the two extreme axial settings thereof to which it may be moved.

It is another and more general object of the invention to provide a mechanism of the character described having embodied therein a minimum number of low cost parts which are capable of easy assembly.

The invention, both as to its organization and method of operation, together with further objects and advantages thereof, will best be understood by reference to the specification taken in connection with the accompanying drawings, in which:

Fig. 1 is a side view illustrating improved tuning control apparatus characterized by the features of the present invention;

Fig. 2 is an end view illustrating the apparatus shown in Fig. 1 as viewed from the left end thereof;

Fig. 3 is an end view of the apparatus shown in Fig. 1 as viewed from the right end thereof;

Fig. 4 is a rear view of the apparatus shown in Fig. 1;

5—5 of Fig. 4, illustrating one of the control elements and the actuating mechanism therefor;

Fig. 6 is a duplication of Fig. 5 illustrating the parts in changed positions;

Fig. 7 is a fragmentary end view, partially in section, illustrating the device for manually adjusting the control or tuning shaft and for releasably locking the control elements of the apparatus against rotation relative to this shaft;

Fig. 8 is a full sectional top view of the parts shown in Fig. 7;

Fig. 9 is a sectional view taken along the lines 9—9 in Fig. 7;

Fig. 10 is a fragmentary sectional view taken along the lines 10—10 in Fig. 8;

Fig. 11 is a sectional view taken along the lines 11—11 in Fig. 8; and

Fig. 12 is a substantial duplication of Fig. 8 with the illustrated parts shown in changed positions.

Referring now to the drawings, the present improved control apparatus is there illustrated in its embodiment in a radio receiver to adjust the gang-connected frequency changing elements of the receiver for the purpose of tuning the receiver to different signal channels, i. e., for the reception of signals radiated at different carrier frequencies. More specifically, the frequency changing means of the receiver comprises a multiple condenser unit 10 supported between two L-shaped bracket pieces 15 and 16 which are rigidly mounted upon the receiver chassis indicated generally at 14. The condenser unit is provided with a rotatable shaft 11 which carries the rotor plates of the condensers and may be rotated through 180° in covering the full tuning range of the receiver. It is journaled in bearing openings through the end members 15 and 16, and also in bearing apertures provided in two spaced apart supporting members 12 and 13 fixedly mounted upon the top wall of the chassis 14. The tuning condensers may be electrically included in the receiver circuit in any conventional manner.

For the purpose of selectively actuating the condenser unit 10 to any desired setting within the tuning range thereof, push button actuated facilities are provided, which as best shown in Fig. 4 of the drawings, comprise a plurality of control or tuning selector elements 22 in the form of heart-shaped cams. These cams are mounted upon the shaft 11 in spaced apart positions axially of this shaft and are normally restrained against rotary movement relative to the shaft. Opposite the control elements are provided an equal number of push button manuals 25, each of which includes a lever 24 pivotally mounted at one end upon a pivot shaft 30, rotatably supports a cam actuating roller 23 at its opposite end, and is provided with a manually operable push button fixedly mounted upon an angular extended projection therefrom. The shaft or pivot rod 30 is supported at its ends by the supporting members 12 and 13, and carries spacing sleeves 31 intermediate the levers 24 for the purpose of maintaining the rollers 23 spaced apart in transverse alignment with their respective associated cams 22.

The members 12 and 13 are also utilized to support the novel tuning indicator means embodied in the apparatus and described with particularity hereinafter. This indicator means is claimed in divisional application Serial No. 554,890, filed September 20, 1944. At this point, it

is noted that this means comprises an elongated channel-shaped member 20 extending longitudinally of the shaft 11 and having its channel-shaped walls disposed within the voids formed at the upper ends of the supporting members 12 and 13 by bending the parts 12a and 13a outwardly therefrom; these parts extending normal to the supporting members and being riveted to the bottom wall of the member 20 to securely anchor this member in place. The channel-shaped member 20 is also provided with side flanges which serve to seat a translucent member 21. This member is suitably apertured to receive lugs 20a struck upwardly from the side flanges of the member 20 and bent over the top surface of the member 21, thereby fixedly to assemble the two members 20 and 21 together. Preferably, the translucent member 21 is painted or etched at the under surface thereof to outline an elongated rectangular surface segment 21a which is left clear to function as a viewing window. At the upper surface thereof and immediately opposite one edge of the window 21a, the member 21 is suitably inscribed with numerals indicating carrier frequencies in kilocycles or with station call letters.

As best shown in Figs. 5 and 6 of the drawings, the levers 24 are spring biased by means of springs 26 individual thereto to normal positions such that the rollers 23 rotatably mounted thereon are out of engagement with the respective associated selector cams 22. Thus the lever 24a is illustrated as being biased to a normal position wherein the roller 23a pivotally supported thereby is wholly out of the path of rotation of the cam 22a. The means for thus biasing the lever 24a comprises a single turn coil spring 26a wrapped around the adjacent spacing sleeve 31 and having one end anchored to the nose 28a of the lever and its opposite end restrained against unwinding movement through engagement with the bottom wall of the channel-shaped member 20. The indicated channel-shaped member is so positioned longitudinally of the shaft 11 as to act as a stop against which the noses 28 of the levers 24 are normally biased. To this end, the side wall 20b of the member 20 is positioned in the paths of rotation of the levers to be engaged by the noses thereof.

Referring now more particularly to the manner in which the selector cams 22 are normally restrained against rotary movement relative to the shaft 11, it will be noted by reference to Fig. 4 of the drawings that these cams are separated by spacing sleeves 32 carried by the shaft 11, and by friction washers 33 against which the ends of the sleeves 32 abut. More specifically, the shaft 11 carries a pair of set screw mounted collars 17 and 18 which are disposed upon opposite sides of the supporting member 12 and function to restrain the shaft against axial movement. The collar 18 is also used as a thrust member against which the selector cams 22, spacing sleeves 32 and washers 33 may be clamped for the purpose of frictionally locking the selector cams against rotation relative to the shaft 11. In order to restrain the washers 33 against rotation relative to the shaft 11, this shaft is provided with diametrically opposed flats 11a and 11b over the length thereof which extends from the collar 18 to the end farthest removed from the tuning condensers 10, and each washer is similarly provided with correspondingly flattened edges in the central aperture through which the shaft 11 extends. The washers 33 are also utilized to limit the extent of

rotation of their respective associated selector cams 22 relative to the shaft 11. To this end, each washer is provided with a portion 36 of reduced diameter terminating in stop steps 37 against which a lug 38 struck out from the associated cam 22 is brought to bear at each limit of the range of rotation of the cam relative to the shaft. In the illustrated arrangement, each washer edge 36 of reduced diameter is sufficiently long to permit the associated cam 22 to be rotated through a maximum angle of 180° relative to the shaft 11. In order to enhance the frictional restraining force exerted upon the selector cams 22, the clamping faces of the washers 36 are stippled or roughened and small sandpaper discs are inserted between the washers 36 and the adjacent faces of the respective associated cams 22 with the sanded surfaces of the discs bearing against the selector cams.

For the purpose of exerting a clamping thrust axially upon the stacked parts 22, 32 and 33, and the sandpaper discs separating the washers 33 from the cams 22, thereby normally to maintain the cams 22 locked against rotary movement relative to the shaft 11, the present improved cam locking and manual tuning device, indicated generally at 40, is provided. In brief, this mechanism comprises a manual actuating shaft 41 which extends normal to the tuning shaft 11 through the front wall of the receiver, is connected to drive the shaft 11 through a pinion 43 and crown gear segment 44 and carries a tuning knob 42. The shaft 41 is journaled for rotary and axial movement in a pair of bracket pieces 60 and 61 struck out from the supporting member 13, and may be moved axially away from the shaft 11 through the pinion 43 without breaking the driving connection between the two shafts 11 and 41. The mechanism also comprises a thrust spring of the compression type which normally exerts a thrust axially of the shaft 11 upon the stacked parts 22, 32 and 33. It further includes a cam and lever mechanism operative in response to axial movement of the shaft 41 outwardly away from the shaft 11 for compressing the thrust spring to the extent required to release the selector cams 22 for rotation relative to the shaft 11. Movement of the manual tuning shaft 41 axially in the reverse direction, i. e., toward the tuning shaft 11 serves to relieve the tension upon the compression spring, with the result that the thrust pressure is again impressed upon stacked elements 22, 32 and 33 to again lock these elements against rotation relative to the shaft 11.

More specifically, the compression spring 51 is confined within two cup-shaped members 52 and 53, the bottom walls 52a and 53a of which are apertured to fit over the two end sleeves 32a and 32c carried by the shaft 11. The sleeve 32a is provided with a radially extending rib 32b against which the bottom wall 52a of the member 52 abuts, and the bottom wall 53a of the opposed cup-shaped member 53 bears against a C-washer 49 which is seated in an annular seat 50 cut in the shaft 11 adjacent the end thereof. Thus the coil spring 51 in thrusting against the C-washer 49 and the end sleeve 32a serves to exert an axially directed thrust against the stacked elements 22, 32 and 33, which normally prevents the selector cams 22 from rotating relative to the shaft 11.

As best shown in Figs. 8 and 12 of the drawings, the cup-shaped members 52 and 53 are nested or telescoped one within the other and are provided with spaced apart flanges 52b and 53b extending radially from the shaft 11 which

are adapted to be acted upon by a lever and cam mechanism to compress the spring 51 and thus release the selector cams for rotation relative to the shaft 11. This mechanism comprises a pair of levers 54 and 55 which extend transversely of the shaft 11 and are commonly supported for rotation about the same center by means of a pivot pin 57 carried by a bracket piece 59 struck out from the end frame member 13. The lever 54 comprises upper and lower parts 54a and 54b joined at the ends remote from the pivot pin 57 by means of an end part 54c. Similarly, the lever 55 comprises upper and lower parts 55a and 55b fitting within the corresponding parts of the lever 54 and joined at the free ends thereof by an end part 55c. The pivoted ends of the identified lever parts are maintained in spaced apart relationship by means of two spacing sleeves 58 disposed upon opposite sides of the bracket 59 and carried by the pivot pin 57. Intermediate the ends thereof, the lever parts 54a and 54b are respectively provided with rounded projections 54e which are adapted to be brought into engagement with the flange 52b of the cup-shaped member 52 upon opposite sides of the shaft 11. Similarly, the lever parts 55a and 55b are respectively provided with rounded projections 55e which are adapted to be brought into bearing engagement with the flange 53b of the cup-shaped member 53 above and below the shaft 11. As best shown in Figs. 9 and 11 of the drawings, the ends of the levers 54 and 55 remote from the pivot pin 57 are crossed so that when these ends are moved apart the projections 54e and 55e are moved toward each other into bearing engagement with the flanges 52b and 53b thereby to compress the spring 51. For the purpose of moving the closed end parts 54c and 55c of the two levers apart, a camming arrangement is provided which includes camming parts 54d and 55d formed integral with the end parts 54c and 55c to extend toward the shaft 11. These camming parts are flared away from each other and are normally engaged by a camming ball or spherical camming part 56 fixedly mounted upon the inner end of the shaft 41, so that when this shaft is pulled away from the shaft 11 the ends of the levers are moved apart to compress the spring 51 in the manner more fully explained below.

As indicated above the shaft 41 is also utilized to rotate the shaft 11 for the purpose of tuning the receiver to stations other than those to which the manuals 25 individually correspond. To this end, a driving connection comprising the pinion 43 carried by the shaft 41 and the meshing crown gear sector 44 carried by the shaft 11 is provided between the two identified shafts. More specifically, the gear sector 44 is fixedly mounted upon the end of the shaft 11 by means of a clamping assembly which includes a washer 45 abutting the C-washer 49 and against which one side of the gear sector bears, a second washer 46 bearing against the opposite side of the gear sector, and a clamping cup 47 fitting over the end of the shaft. Clamping pressure is exerted upon the stacked parts 45, 44, 46, 47 by means of a clamping screw 48 extending through the apertured bottom wall of the cup 47 and threaded into the end of the shaft 11. In order to permit axial movement of the shaft 41 without breaking the driving connection between this shaft and the tuning shaft 11, the pinion 43 is freely movable axially of the shaft 41 but is locked against rotation relative to this shaft. To provide this form of connection between the two parts 41

and 43, the shaft 41 is provided with a flattened portion 41a, and the hub part 43a of the pinion 43 is provided with a half circle slot 43b within which is disposed a wire-like locking element 62. More specifically, this element tightly embraces the flattened surface 41a of the shaft 41 and the unslotted circumference of the pinion hub 43b to lock the two parts 41 and 43 against relative rotary movement while permitting relative axial movement therebetween. The pinion 43 is restrained against movement in a direction axially of the shaft 41 by positioning the same between the bracket parts 60 and 61 in which the shaft 41 is journaled, thus maintaining this pinion in meshing engagement with the crown gear sector 44 regardless of the axial position to which the shaft 41 is moved.

In order to maintain a slight clamping pressure upon the selector cams 22 when the spring 51 is compressed to release these cams for adjustment relative to the shaft 11, a dished spring washer 34 is provided between the two washers 33a and 33b which are disposed between the end of the end sleeve 32a and the cam 22a. This spring washer has the function of restraining the cams 22 against rotation relative to the shaft 11 except when a positive force is applied to one of the cams to produce such relative rotation in the manner described below. To provide for adjustment of the clamping force normally exerted axially upon the cams 22 by the compression spring 51, a two part spacing sleeve 9 is provided between the two center cams 22c and 22d. Specifically, this sleeve comprises two tubular parts 9a and 9b, the first of which is threaded into the second so that the length of the sleeve may be changed as required by rotating one part relative to the other. This arrangement constitutes a convenient means for obtaining the desired spring thrust upon the cams 22 regardless of manufacturing discrepancies in the parts making up the cam locking assembly. Thus after the assembly of a particular device is completed, the sleeve part 9a may be threaded out of the sleeve part 9b to compress the spring 51 until the cams 22 are positively clamped against rotation relative to the shaft 11.

From the above explanation it will be understood that normally the selector cams 22 are locked against rotation relative to the shaft 11 and that these cams occupy different angular positions relative to the shaft 11, such that the tuning condensers 10 may be operated to signal channel settings respectively corresponding to the different selector elements through the selective manipulation of the manuals 25. If, for example, it is desired to tune the receiver for the reception of the particular signal corresponding to the manual 25a, the push button of this manual is pushed downwardly from the position illustrated in Fig. 5 of the drawings to the position illustrated in Fig. 6 of the drawings. During the resulting pivotal movement of the lever 24a, the roller 23a is brought into engagement with the periphery of the selector cam 22a, following which the two engaged parts 23a and 22a coact to rotate the tuning shaft 11 to the particular angular setting corresponding to the desired signal channel. This tuning position of the shaft is reached when the roller 23a is moved to engage the low point of the cam 22a. After it is reached, the manual 25a may be released to return to its normal position under the influence of the biasing spring 26a. In a manner entirely similar to that just described, the other push button

75

manuels 25 may be selectively actuated for the purpose of selectively tuning the receiver for the reception of the other signals to which these manuals respectively correspond. Tuning of the receiver to a signal within the signal reception band of the receiver, but not corresponding to one of the push button manuals 25, is accomplished through manual actuation of the knob 42 to rotate the shaft 41 and thus rotate the tuning shaft 11 through the driving connection afforded by the pinion 43 and the gear sector 44.

As previously indicated, in order to adjust the angular settings of the selector cams 22 relative to the shaft 11, thereby to change the signal channels to which these cams are respectively capable of tuning the receiver, the clamping pressure exerted axially of the shaft upon the cams is partially released. To this end, the knob 42 and shaft 41 are pulled outwardly from the front wall of the receiver, thereby to move the spherical camming part 56 up the inclined camming surfaces of the lever parts 54d and 55d toward the end parts of the two levers. During such movement, the end parts 54c and 55c of the two levers are spread apart and the intermediate portions of the levers are moved toward each other. As a result, the projections 54e and 55e are brought to bear against the flanges 52b and 53b to squeeze these flanges together and thus compress the coil spring 51, thereby to relieve the clamping force exerted axially upon the selector cams 22. This force is not wholly relieved, however, due to the action of the spring washer 34 in exerting an axial thrust upon the cams 22 through the washers 33a and 33b. As the spherical camming part 56 is moved away from the shaft 11 it passes out of engagement with the lever camming parts 55d and 54d over the ridge-like surfaces 54g and 55g and into engagement with the inner surfaces 54f and 55f of the lever end parts 55c and 54c. Due to the spreading apart of the lever end parts, the normally parallel surfaces 54f and 55f thereof tend to become flared away from each other in a direction which is the reverse of the direction of flare between the camming parts 55d and 54d. In other words a wedging action is produced between the engaged surfaces of the parts 56, 54c and 55c which has the effect of resisting axial movement of the shaft 41 back toward the shaft 11. Thus an over center arrangement is provided which has the effect of restraining the shaft 41 in its axial position away from the shaft 11.

Following the operations just described, the selector cam 22a, for example, may be set to a new angular position relative to the shaft 11, so that it will coact with the manual 25a to tune the receiver for the reception of a different desired signal. To this end, the knob 42, shaft 41 and driving parts 43 and 44 are first operated manually to tune the receiver to the desired signal frequency. With the desired signal being received, the knob 42 is manually held against further rotation and the manual 25a is actuated for the purpose of rotating the selector cam 22a to the new angular setting relative to the shaft 11. After the new setting is thus established the manual 25a may be released. In a manner entirely similar to that just described, any one or all of the five remaining selector cams 22 may be set to new positions relative to the shaft 11. In this regard it is reiterated that the spring washer 34 maintains sufficient axial pressure upon the cams to prevent the same from being rotated relative to the shaft 11 otherwise than

in the manner just described. In other words, the spring 34 prevents the desired angular settings of the cams relative to the shaft 11 from being disturbed when once established.

After all of the control elements have been adjusted in the manner just explained they may be reclamped against movement relative to the shaft 11 by pushing upon the knob 42 to move the spherical camming part 56 from between the lever end parts 54c and 55c back toward the shaft 11. After the camming part 56 is moved to again engage the lever camming parts 54d and 55d, the coil spring 51 in thrusting against the cup-shaped members 52 and 53 acts through the levers and their camming parts 54d and 55d to facilitate return movement of the camming part 56 and the shaft 41 to the normal positions thereof. Also, in expanding against the bottom walls of the cup-shaped members 52 and 53 the coil spring 51 again thrusts against the selector cams 22 to restrain these cams against rotation relative to the shaft 11.

From the above explanation, it will be understood that the selector cam clamping mechanism may be actuated at will to release the cams 22 for adjustment to any desired angular positions relative to the shaft 11 and to reclamp the cams in the positions to which they are adjusted. It will also be understood that this is accomplished by utilizing axial movement of the manually operable shaft 41 to effect relative movement between the levers 54 and 55 in a direction extending axially of the shaft 11. Further, the arrangement is such that the driving connection between the two shafts 41 and 11 is not broken regardless of the axial setting occupied by the shaft 41. In this regard it is noted that normally the lever projections 54e and 55e only lightly engage the flanges 52b and 53b so that rotation of the shafts 41 and 11 is in no way impeded by such engagement. Also, when the spring 51 is compressed to release the selector cams 22 for adjustment relative to the shaft 11, the assembly comprising the parts 32a, 32c, 52, 53 and 51 is effectively locked against rotation through engagement of the lever projections 54e and 55e with the flanges 52b and 53b. Under these circumstances, however, the shaft 11 is free to turn within the sleeves 32a and 32c so that rotation of the shaft 11 is only slightly impeded.

Referring now more particularly to the apparatus which is provided to indicate the station to which the receiver is tuned, it is pointed out above that this apparatus comprises the translucent member 21 carried by the channel-shaped member 20, which two parts are fixedly supported by the supporting members 12 and 13. This apparatus further comprises translatable indicating means in the form of a pointer 65 which is linearly movable back and forth longitudinally of the two members 20 and 21 to settings indicative of the carrier frequency to which the receiver is tuned. More specifically, this pointer is in the form of a wire-like element having an indicated leg 65a disposed within the channel of the member 20 and extending transversely across the indicating window 21a, and a second leg 65b which extends normal to the leg 65a through a narrow guide slot 20c extending longitudinally of the bottom wall of the channel-shaped member 20 to engage the helical camming surface of a rotatable camming member 67. For the purpose of translating the pointer 65 along the slot 20c, a driving connection is provided between the shaft 11 and this pointer which includes a gear segment 19

fixedly mounted upon the collar 17. This gear segment meshes with a small gear 71 which is connected to drive the camming member 67 through a drive pin 70 which is journaled in a bearing part carried by the frame member 12 and is anchored within the right end of the tubular camming member 67. The gear segment 19 and pinion 71 are stamped parts formed from thin gauge stock, and in order to maintain the same in meshing engagement, dished fender discs 72 and 73 are provided upon opposite sides of the pinion 71 to embrace the peripheral segment of the gear 19 which meshes with the pinion 71.

More specifically considered, the camming member 67 is in the form of a flat-wound metal strip, the edges of which are displaced so that a helical camming groove 68 of only slightly greater width than the diameter of the pointer 65 is formed therebetween. Thus the edges of the strip act as helical camming surfaces. The leg 65b of the pointer 65 extends through the groove 20c to slidably engage the helical camming surfaces, and is anchored to an elongated travelling element 66 which is disposed within the tubular camming member 67 and is slideable longitudinally of this member as the pointer 65 is translated through engagement of the leg 65b with the camming surfaces. As best shown in Fig. 5 of the drawings, the travelling element 66 is in the form of a rod segment and is slotted longitudinally along one side to receive the end portion 65c of the pointer. This end portion of the pointer extends normal to the pointer leg 65b and may be soldered or otherwise bonded to the travelling element 66 within the slot in which it is disposed to provide a rigid connection therebetween. As indicated above, the means for rotatably supporting the camming member 67 includes the pin 70 journaled in the bearing part carried by the frame member 12. It also includes a pin 69 journaled in the frame member 13 and fixedly connected to the left end of the member 67.

As shown in Fig. 2 of the drawings, the gear segment 19 not only functions to drive the camming member 67, but is also utilized to limit the angle of rotation of the shaft 11. To this end, the frame member 12 is provided with a struck out stop part 12b disposed in the path of rotation of the gear segment 19 to be engaged by the straight edge portions of this gear segment when the shaft is rotated to the limits of its range of rotation.

Referring now more particularly to the operation of the improved indicating apparatus, it will be understood that when the tuning shaft 11 is rotated, either through actuation of the knob 42 or one of the manuals 25, the camming member 67 is rotated in a corresponding direction through the driving connection afforded by the meshing engagement of the gear segment 19 with the pinion 71. Since the pointer 65 is prevented from rotating with the camming element 67 through engagement of the leg 65b with the edges of the guide slot 20c, the rotary movement of the camming member is converted into translatory movement of the pointer, due to the following movement of the leg 65b along the helical cam groove 68. Translatory movement of the pointer 65 is obviously accompanied by sliding movement of the travelling element 66 within the tubular camming member 67. The extent of pointer movement per unit angle of rotation of the shaft 11 is, of course, determined by the pitch of the helical groove 68 and the tooth ratio between the gears 19 and 71. In the illustrated arrange-

ment, these factors are so determined that the pointer 65 will move over the full scale range in response to rotation of the tuning shaft 11 through an angle of 180°. Further, the spacing of the scale indicia provided along the upper edge of the viewing window 21a is accurately calibrated so that the pointer 65 in indexing any scale marking provides an accurate indication of the signal channel to which the receiver is tuned. Thus an exceedingly simple, rugged and cheap structure is provided for accurately indicating the particular station to which the receiver is tuned. On this point, it is noted that the use of guide rails or other extraneous supporting members for the translatable pointer 65 is rendered unnecessary by utilizing the camming member 67 as substantially the sole means of support for the pointer. Further, the elongated construction of the travelling element 66 positively precludes any tendency of the pointer to twist about the axis of the pointer part 65b and insures non-binding sliding movement of this element through the cam member 67.

While there has been described what is at present considered to be the preferred embodiment of the invention, it will be understood that various modifications may be made therein which are within the true spirit and scope of the invention as defined in the appended claims.

I claim:

1. In radio tuning apparatus which includes a tuning shaft rotatable through a desired tuning range and a plurality of tuning selector elements carried by said shaft; spring means normally restraining said selector elements against movement relative to said shaft, a manually operable element, means supporting said element for movement in two directions, means for rotating said shaft to any setting within said range in response to a corresponding movement of said manually operable element in one of said two directions, and means responsive to movement of said manually operable element in the other of said two directions for relieving the restraining force exerted by said spring means upon said selector elements, thereby to release said selector elements for movement relative to said shaft.

2. In radio tuning apparatus which includes a tuning shaft rotatable through a desired tuning range and a plurality of tuning selector elements carried by said shaft; spring means normally restraining said selector elements against movement relative to said shaft, a manually operable element, means supporting said element for rotary and axial movement, means responsive to rotation of said manually operable element for correspondingly rotating said shaft to different settings within said tuning range, and means responsive to axial movement of said manually operable element for relieving the restraining force exerted by said spring means upon said selector elements, thereby to release said selector elements for movement relative to said shaft.

3. In radio tuning apparatus which includes a tuning shaft rotatable through a desired tuning range and a plurality of tuning selector elements carried by said shaft; spring means normally restraining said selector elements against movement relative to said shaft, a manually operable element, means supporting said element for rotary and axial movement, means interconnecting said shaft and said manually operable element to provide a driving connection for rotating said shaft to different settings within said

range in response to rotation of said manually operable element, and means responsive to axial movement of said manually operable element for relieving the restraining force exerted by said spring means upon said selector elements, thereby to release said selector elements for movement relative to said shaft, without breaking the driving connection between said manually operable element and said shaft.

4. In radio tuning apparatus which includes a tuning shaft rotatable through a desired tuning range and a plurality of tuning selector elements carried by said shaft, a second shaft, a pinion carried by said second shaft, means restraining said pinion and second shaft against relative rotary movement while permitting relative axial movement therebetween, means supporting said second shaft for rotary and axial movement, said pinion being restrained against axial movement during axial movement of said second shaft, gear means interconnecting said pinion and said tuning shaft to provide a driving connection between said shafts at all axial settings of said second shaft, whereby said tuning shaft may be operated to different settings within said tuning range in response to rotation of said second shaft, and means controlled by axial movement of said second shaft for releasably locking said selector elements against movement relative to said tuning shaft.

5. In radio tuning apparatus which includes a tuning shaft rotatable through a desired tuning range and a plurality of tuning selector elements spaced axially along said shaft; the means for releasably locking said selector elements against rotation relative to said shaft which comprises a compression spring embracing said shaft and normally exerting a thrust force axially of said shaft against said selector elements which serves to restrain said selector elements against rotation relative to said shaft, a pair of opposed cup-shaped members supported for relative movement axially of said shaft and between which said compression spring is confined, actuating parts fixedly carried by said members and extending radially from said shaft, and means for moving at least one of said actuating parts axially toward the other actuating part, thereby to compress said spring and thus release said selector elements for rotation relative to said shaft.

6. In radio tuning apparatus which includes a tuning shaft rotatable through a desired tuning range and a plurality of tuning selector elements spaced axially along said shaft; the means for releasably locking said selector elements against rotation relative to said shaft which comprises a compression spring embracing said shaft and normally exerting a thrust force axially of said shaft against said selector elements which serves to restrain said selector elements against rotation relative to said shaft, a pair of opposed cup-shaped members supported for relative movement axially of said shaft and between which said compression spring is confined, a stop element anchored to said shaft and projecting radially outward therefrom to act as a stop against which one of said cup-shaped members bears, a driving gear carried by said shaft, means including said stop element for restraining said gear against rotation relative to said shaft, and means for moving said cup-shaped members axially toward each other, thereby to compress said spring and thus release said selector elements for rotation relative to said shaft.

7. In radio tuning apparatus which includes a tuning shaft rotatable through a desired tuning range and a plurality of tuning selector elements spaced axially along said shaft; the means for releasably locking said selector elements against rotation relative to said shaft which comprises a compression spring embracing said shaft and normally exerting a thrust force axially of said shaft against said selector elements which serves to restrain said selector elements against rotation relative to said shaft, a pair of opposed cup-shaped members supported for relative movement axially of said shaft and telescoped one within the other, said spring being housed within said members and having its ends tensioned against the bottoms of said members, said shaft having an annular seat adjacent the bottom wall of the cup-shaped member farthest removed from said selector elements, a C-washer disposed in said seat to act as a stop against which the bottom wall of said last-named cup-shaped member bears, a driving gear carried by said shaft, means for clamping said gear against said C-washer, thereby to restrain said gear against rotation relative to said shaft, said cup-shaped members having flanges extending radially outward from said shaft and spaced axially along said shaft, and means for moving said flanges toward each other, thereby to compress said spring within said cup-shaped members and thus release said selector elements for rotation relative to said shaft.

8. In a control device which includes a plurality of control elements carried by a rotatable shaft; the means for releasably locking said control elements against rotation relative to said shaft which comprises a compression spring embracing said shaft and normally exerting a thrust force axially of said shaft against said control elements which serves to restrain said control elements against rotation relative to said shaft, a pair of opposed cup-shaped members supported for relative movement axially of said shaft and between which said compression spring is confined, said members including flanges extending radially outward from said shaft, a lever mechanism including levers extending transversely of said shaft and provided with parts engageable with said flanges to move said cup-shaped members toward each other and thus compress said spring to relieve the thrust force exerted upon said control elements when said levers are moved relative to each other, and means for producing relative movement between said levers, thereby to release said selector elements for rotation relative to said shaft.

9. In a control device which includes a plurality of control elements carried by a rotatable shaft; the means for releasably locking said control elements against rotation relative to said shaft which comprises a compression spring embracing said shaft and normally exerting a thrust force axially of said shaft against said control elements which serves to restrain said control elements against rotation relative to said shaft, a pair of opposed cup-shaped members supported for relative movement axially of said shaft and between which said compression spring is confined, said members including flanges extending radially outward from said shaft, a lever mechanism including levers extending transversely of said shaft and provided with parts engageable with said flanges to move said cup-shaped members toward each other and thus compress said spring to relieve the thrust force exerted

upon said control elements when said levers are moved relative to each other, a second shaft, means supporting said second shaft for rotary and axial movement, means providing a driving connection between said shafts at all axial settings of said second shaft, and cam means including interengaging parts respectively carried by said second shaft and said levers for producing relative movement between said levers in response to axial movement of said second shaft, thereby to release said control elements for rotation relative to said first-named shaft.

10. In a control device which includes a plurality of control elements carried by a rotatable shaft; the means for releasably holding said control elements against rotation relative to said shaft which comprises a pair of elongated members extending transversely of said shaft, means pivotally supporting said members to one side of said shaft, means for moving said members relative to each other in a direction extending axially of said shaft, and means controlled by said members for normally clamping said control elements against rotation relative to said shaft and for releasing said elements for rotation relative to said shaft in response to said relative movement between said members.

11. In a control device which includes a plurality of control elements carried by a rotatable shaft; the means for releasably holding said control elements against rotation relative to said shaft which comprises a lever mechanism provided with levers extending transversely of said shaft, means for moving said levers relative to each other in a direction extending axially of said shaft, and means controlled by said relative movement between said levers for releasably restraining said control elements against rotation relative to said shaft.

12. In a control device which includes a plurality of control elements carried by a rotatable shaft, the means for releasably holding said control elements against rotation relative to said shaft which comprises a pair of elongated members extending transversely of said shaft, means pivotally supporting said members to one side of said shaft, said members having crossed end portions disposed upon the opposite side of said shaft, means coacting with the crossed end portions of said members for drawing said members toward each other, and means controlled by said members for normally restraining said control elements against rotation relative to said shaft and for releasing said elements for rotation relative to said shaft in response to said movement of said members toward each other.

13. In a control device which includes a plurality of control elements carried by a rotatable shaft, the means for releasably holding said control elements against rotation relative to said shaft which comprises a pair of elongated members extending transversely of said shaft, means pivotally supporting said members to one side of said shaft, said members having crossed end portions disposed upon the opposite side of said shaft, a second shaft extending substantially at right angles to said first-named shaft, means supporting said second shaft for axial movement away from said first-named shaft, said second shaft and the crossed end portions of said members being provided with coacting camming parts for moving said members toward each other in response to axial movement of said second shaft away from said first-named shaft, and means controlled by said members for normally re-

straining said control elements against rotation relative to said first-named shaft and for releasing said elements for rotation relative to said shaft in response to said movement of said members toward each other.

14. In a control device which includes a plurality of control elements carried by a rotatable shaft; levers extending transversely of said shaft, means pivotally supporting said levers to one side of said shaft, said levers being provided with crossed end portions upon the opposite side of said shaft, said end portions including camming parts flared away from each other, a second shaft extending substantially at right angles to said first-named shaft and provided with a spherical camming part disposed between said flared camming parts, means supporting said second shaft for axial movement away from said first-named shaft, whereby said levers are moved toward each other in response to movement of said second shaft axially away from said first-named shaft, a compression spring normally thrusting against said control elements to restrain said elements against rotation relative to said first-named shaft, and means for squeezing said compression spring in response to movement of said levers toward each other, thereby to release said control elements for rotation relative to said first-named shaft.

15. In a control device which includes a plurality of control elements carried by a rotatable shaft; levers extending transversely of said shaft, means pivotally supporting said levers to one side of said shaft, said levers being provided with crossed end portions upon the opposite side of said shaft, said end portions including camming parts which extend parallel to each other and flare away from each other at their extremities, a second shaft extending substantially at right angles to said first-named shaft and provided with a spherical camming part disposed between said flared camming parts, means supporting said second shaft for axial movement away from said first-named shaft, whereby said spherical camming part is moved between the flared portions of first-named camming parts onto the parallel extending portions thereof to move the levers toward each other, a compression spring normally thrusting against said control elements to restrain said elements against rotation relative to said first-named shaft, means for squeezing said compression spring in response to movement of said levers toward each other, thereby to release said control elements for rotation relative to said first-named shaft, and gear means providing a driving connection between said shafts regardless of the axial setting of said second shaft, the engagement of said spherical camming part with the parallel extending portions of said first-named camming parts when said second shaft is withdrawn preventing inadvertent axial movement of said second shaft back toward said first-named shaft.

16. In a control device which includes a plurality of control elements carried by a rotatable shaft, a compression spring normally thrusting against said control elements to restrain said elements against rotation relative to said shaft, a second shaft extending transversely of said first-named shaft, means supporting said second shaft for rotary and axial movement, means providing a driving connection between said shafts at all axial settings of said second shaft, a spherical camming part carried by the end of said second shaft, a pair of levers extending transversely of

said first-named shaft and provided with camming parts engaging said spherical camming part, said camming parts coacting to move said levers toward each other in response to movement of said second shaft axially away from said first shaft, and means interconnecting said levers and said spring to bias said second-named camming parts into engagement with said spherical camming part and to compress said spring in response to movement of said levers toward each other, thereby to release said control elements for rotation relative to said first-named shaft.

17. In a control device which includes a plurality of control elements carried by a rotatable control shaft; a second shaft, means supporting said second shaft for axial movement away from said control shaft, a lever mechanism including a pair of levers extending transversely of said control shaft, coacting camming means carried by said levers and said second shaft for moving said levers relative to each other and for restraining said second shaft in a set position away from said control shaft in response to movement of said second shaft axially away from said control shaft, and means controlled by said relative movement between said levers for releasably restraining said control elements against movement relative to said control shaft.

18. Tuning apparatus for a radio receiver, comprising a rotatable shaft for actuating the tuning means of the receiver, station selector elements spaced axially along said shaft, manuals individual to said selector elements and selectively engageable therewith to selectively rotate said shaft to different settings, each of said manuals including a pivotally supported lever and spring means biasing the lever away from its associated selector element, an elongated channel-shaped member extending longitudinally of said shaft and positioned to act as a stop against which said levers are normally biased, said member having a longitudinally extending guide slot in the bottom wall thereof, translatable indicator means including an element extending through said slot to guide said indicator means, and means for translating said indicator means along said channel-shaped member as said shaft is rotated to tune the receiver.

19. Tuning apparatus for a radio receiver, comprising a rotatable shaft for actuating the tuning means of the receiver, station selector elements spaced axially along said shaft, manuals individual to said selector elements and selectively engageable therewith to selectively rotate said shaft to different settings, each of said manuals including a pivotally supported lever and spring means biasing the lever away from its associated selector element, an elongated channel-shaped member extending longitudinally of said shaft and positioned to act as a stop against which said levers are normally biased, said member having a longitudinally extending guide slot in the bottom wall thereof, an elongated camming member disposed beneath said channel-shaped member in alignment with said groove and provided with a helical camming surface, means for rotating said camming member as said shaft is rotated, and translatable indicator means including an element extending through said slot and provided with a cam follower slidably engaging said camming surface, whereby said indicator means is translated along said channel shaped member during rotation of said camming member.

20. Tuning apparatus for a radio receiver, comprising a rotatable shaft for actuating the tuning

means of the receiver, station selector elements spaced axially along said shaft, manuals individual to said selector elements and selectively engageable therewith to selectively rotate said shaft to different settings, each of said manuals including a pivotally supported lever and spring means biasing the lever away from its associated selector element, an elongated channel-shaped member extending longitudinally of said shaft and positioned to act as a stop against which said levers are normally biased, said member having a longitudinally extending guide slot in the bottom wall thereof, an elongated tubular camming member disposed beneath said channel-shaped member in alignment with said slot and comprising an edge-wound strip having its edges displaced to define a helical camming groove, an elongated traveling element disposed within said camming member and slidably movable longitudinally of said camming member, translatable indicator means including a wire-like element extending through said slot and groove and anchored to said traveling element, whereby said indicator means is at least in part supported by said camming member and is translated along said slot when said camming member is rotated, means supporting said camming member for rotation, and means providing a driving connection between said shaft and said camming member.

21. In a control device which includes a plurality of adjustable control-position-selector elements carried by a rotatable shaft; the combination of mechanism for releasably restraining

said selector elements against movement relative to said control shaft including yieldable means on said shaft adapted to be operatively connected with said selector elements, a movable unit, means mounting said unit in a position at right angles to said control shaft and mounted both for rotation and for longitudinal movement of said unit, a lever mechanism comprising a pair of pivoted elements movable toward and away from one another and operatively connected with said yieldable means, cam means operatively connecting said movable unit and said lever mechanism and movable upon one direction of longitudinal movement of said unit to operate the lever mechanism and compress the yieldable means and movable upon the other direction of longitudinal movement of said unit to permit the expansion thereof, and means maintained in an operative connection between said movable unit and said control shaft to rotate said control shaft upon rotary movement of said movable unit.
